(57) **CLAIM**

The ornamental design for a breast milk collector, as shown and described.

DESCRIPTION

FIG. 1 is a perspective view of a breast milk collector showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any shading and cross-hatching are not features of the design but are utilized to illustrate the surface contours of the breast milk collector design in the drawings.

The broken lines and adjacent surfaces shown without surface shading illustrate portions of the article that form no part of the claimed design.
